(57) **CLAIM**

The ornamental design for an emergency vehicle light-bar, as shown.

DESCRIPTION

FIG. 1 is a perspective view of an emergency vehicle light-bar showing my new design;

FIG. 2 is a front thereof;

FIG. 3 is a back view thereof;

FIG. 4 is a right side view thereof;

FIG. 5 is left side view thereof;

FIG. 6 is a top view thereof; and,

FIG. 7 is a bottom view thereof.

In the drawings, the broken line showing of mounting hardware depicts environmental subject matter and forms no part of the claim.
